UNITED STATES PATENT OFFICE.

FRED FREDRICKSON, OF CHICAGO, ILLINOIS.

COLLAR-BUTTON ATTACHMENT OR GUARD.

Application filed March 7, 1921. Serial No. 450,510.

To all whom it may concern:

Be it known that I, FRED FREDRICKSON, a citizen of the United States, residing at Chicago, in the county of Cook and State of Illinois, have invented new and useful Improvements in Collar-Button Attachments or Guards, of which the following is a full, clear, concise, and exact description, reference being had to the accompanying drawing, forming a part of this specification.

My invention relates to improvements in collar button attachment or guard, and has for its object the production of a device by means of which a collar can be buttoned and kept buttoned while the tie is being put in place.

A further object is the production of a device that will hold the button from being forced out of position while the tie is being tied.

A further object is the production of a device of simple construction, and one that can be cheaply manufactured.

These and such other objects as may appear hereinafter are attained by my device, embodiments of which are illustrated in the accompanying drawing, in which—

Figure 1 represents a perspective view of my device in position on a collar; Fig. 2 is a side elevation of the device C of Fig. 1.

Like letters of reference indicate like parts in the several figures of the drawing.

Referring now to the drawings—a represents a collar, b the button, and c my improved device. The device, as shown in Figs. 1 and 2, comprises a curved strip or sheet of metal c, having near its upper end a circular opening d with an extended slot e. The opening d is large enough to permit slipping the device over the button b, the device itself being pulled down, permitting the shank of the button to enter the extended slot e, where it will be held against dislodgment.

It is understood, of course, that the style shown in Figs. 1 and 2 may have an extended end formed with an integral button-hook, if desired. The member c is slightly curved

forwardly from a point immediately below the button head clearing hole d, so as to prevent any danger of its slipping out of place when in use, and to conform to the contour of the body.

In the ordinary course of events, in putting on a collar and tie, great difficulty has been experienced, especially in the event of the button hole being somewhat worn, or the collar confining the tie too tightly, so that when the ends are pulled together in tying or making up the tie, the two ends of the collar are pulled together, pulling one of the sides away from the button. This unfortunately happens after the tie is in place, in attempting to adjust the tie, making it very annoying to the wearer, as it is often difficult to rebutton the collar with the tie in place.

By the use of my device, however, after the collar is buttoned, my device is slipped over and pulled down, with the shank of the button in the groove e; then it is possible to pull the tie in any desired way in evening up the ends or making them to conform with each other, without any danger of unbuttoning the collar. The device itself is curved, lays out of the way, and forms no obstruction whatever to the tying of the tie; and when the tie is in proper place,—up snugly in position,—it is necessary simply to push up my device until the head of the button is within the opening d, and the device can be slipped off the button and put in the pocket.

I appreciate the fact that this is a very simple device, and yet it is one that seems to possess great merit, and one that should be in great demand by the public.

While I have illustrated a certain form and embodiment of my device, it is clear, of course, that other forms may be used without departing from the spirit of my invention.

Having thus described my invention, I claim—

As a new article of manufacture, a shirt collar lock and button guard comprising a flat narrow strip of metal having an opening at one end thereof arranged to be placed over the head of a collar button in use and

lock down behind the head so as to hold the button and collar in place, said opening being circular at one end of sufficient size to pass over the head of a collar button and extending into a restricting slot having parallel sides smaller than the head but adapted to receive the shank of the collar button so

as to lock between the head and collar, the depending end of said strip being curved outwardly below the collar to conform to the body of the wearer. 10

In witness whereof, I have hereunto subscribed my name.

FRED FREDRICKSON.
